UNITED STATES PATENT OFFICE.

ARTHUR R. HAVENER, OF WAYLAND, MASSACHUSETTS, ASSIGNOR TO JUDSON L. THOMSON MANUFACTURING CO., OF WALTHAM, MASSACHUSETTS, A CORPORATION OF MASSACHUSETTS.

FASTENER-SETTING MECHANISM.

Application filed April 22, 1926. Serial No. 163,923.

This invention relates to an improved fastener setting mechanism.

The object of the invention is to provide a setting mechanism which will feed, position and drive and clinch in sheet material pronged fasteners having an annular head.

The invention consists in the improved mechanism hereinafter set forth in the specification and particularly pointed out in the claims.

Referring to the drawings:—

Figure 1 is a side elevation of a portion of my improved fastener setting mechanism.

Fig. 2 is a front elevation of the same.

Fig. 3 is a sectional elevation taken on the line 3—3, Fig. 2 and with the fastener fingers closed together and supporting a pronged fastener thereon.

Fig. 4 is a figure similar to Fig. 3, but with the driver and plunger lowered part way and the fastener supporting fingers spread part way.

Fig. 5 is a sectional elevation similar to Figs. 3 and 4, but showing the plunger and driver still further lowered and the fastener supporting fingers spread wide open.

Fig. 6 is a section similar to Figs. 3, 4 and 5 with the driver and plunger in their lowermost positions, the fastener supporting fingers spread wide apart, and the fastener driven and clinched in a piece of material.

Fig. 7 is a detail sectional plan taken on the line 7—7, Fig. 3.

Fig. 8 is a detail sectional plan taken on line 8—8, Fig. 3.

Like numerals refer to like parts throughout the several views of the drawings.

In the drawings, 10 is the frame of the machine. 11 is a hopper which feeds the pronged fasteners down a raceway 12 to be delivered one by one between a pair of fingers 13 and 14 pivotally supported at 15 and 16 upon a stationary holder 17 comprising a base 18 and an upwardly extending shank 19, which is adjustably supported in a head 20 of the frame 10 by an arm 21 and adjusting screw 22, so that the height of the fingers may be adjusted as may be desired.

The fingers 13 and 14 are drawn toward each other by a spring 23, and each of said fingers has a semi-circular recess 24 adjacent its lower end, and plates 25 and 26 are fastened to the lower ends of the fingers 13 and 14 and when the fingers are in their nor-

mally closed position as in Fig. 3, the 55 pronged fastener 27 rests upon these plates 26 within the recesses 24, which approximately surround the prongs of the fastener.

A stop plate 28 is fastened to the under side of the base 18 and has a pair of ears 29 and 30 which project therefrom into alignment with the fingers 13 and 14, so that when the spring 23 is free to act it draws said fingers toward each other until they abut against the ears 29 and 30 as illustrated 65 in Figs. 3 and 7.

A driver 31 is slidably mounted in the head 20 and has a reciprocatory motion imparted thereto by a bifurcated link 32 pivotally attached at 33 thereto, to which a reciprocatory motion is imparted by a lever 34 which has a rocking motion imparted thereto by mechanism not shown in the drawings but well known to those skilled in this art. The driver 31 is provided in its lower end 75 with an annular groove 35 adapted to receive the annular head 36 of the fastener 27, and within the driver 31 there is slidably mounted a plunger 37 which is moved downwardly in the driver 31 by a spring 38. The plunger 80 37 is held positioned in the driver 31 by a cross pin 39 which projects into a slot 40 provided in one side of the driver 31. Normally, the lower end or forward end of the plunger 37 projects beyond the forward end 85 of the driver 31.

An anvil 41 is positioned upon an arm 42 of the frame 10 in alignment with the plunger 37 and driver 31, said anvil being provided with an annular groove 43, and the 90 material 44 in which the fastener is to be driven and clinched is placed upon this anvil.

The general operation of the mechanism hereinbefore specifically described is as follows:—

Pronged fasteners 27, having an annular head, are fed from the hopper 11 down the raceway 12 and one by one are fed into the position illustrated in Fig. 3 where the fastener is shown resting upon the plates 26 within the circular recess 24, the fingers 13 and 14 being at that time in their closed position and held in said closed position by the spring 23 and abutting against the ears 29 and 30. The driver 31 and the plunger 37 carried thereby now descend from the position illustrated in Fig. 3 to that illustrated in 100 105

Fig. 4. The lower end of the plunger 37 is beveled so that it enters the annular bore of the head of the fastener 27 and is forced into frictional engagement therewith by the driver 31 through the spring 38.

During this downward movement of the driver and plunger and after the plunger has entered the bore of the fastener, the head of the fastener enters the annular 10 groove 35 in the driver 31, and then upon further downward movement the fingers 13 and 14 are forced apart by the fastener as illustrated in Fig. 4 until, as in Fig. 5, the fastener is brought downwardly toward the 15 material 44 which is then resting upon the anvil 41 as illustrated in Fig. 5. At this time the fingers are wide apart and the plates 26 are resting against the sides of the driver 31.

Now upon a further downward movement, the prongs of the fastener are driven through the material and clinched therein by engagement with the anvil 41. The parts are then returned to the relative positions illustrated in Fig. 3 ready for the setting operation to be repeated.

The reciprocatory motion of the driver 31 and plunger 37 is accomplished by means of the lever 34 and other mechanisms not shown in the drawings, but well known to those skilled in this art.

The material in which the fasteners are set is positioned upon the anvil 41 and fed along the same to space the fasteners apart, by hand.

I claim:

1. A machine for setting an annular-pronged fastener having, in combination, a driver provided with an annular groove in its end surface adapted to receive the head portion of said fastener, a spring-actuated plunger in said driver adapted to frictionally engage the inner face of said annular fastener and hold it positioned within said groove, the forward end of said plunger normally projecting out of said driver beyond the annular groove therein, an anvil in alignment with said driver, and mechanism to impart a reciprocatory motion to said driver and plunger, whereby the prongs of said fastener may be clinched in a piece of ma-

terial interposed between the driver and anvil and the plunger caused to contact with the material and to be thereby forced out of the fastener and rearwardly into the 55 driver.

2. A mechanism for setting an annular pronged fastener having, in combination, a driver provided with an annular groove adapted to receive the head portion of said fastener, a spring-actuated plunger in said driver adapted to frictionally engage the inner face of said annular fastener and hold it positioned thereon, the forward end of said plunger normally projecting out of said driver beyond the annular groove therein, an anvil in alignment with said driver, a yielding and laterally movable support for said fastener interposed between said driver and anvil, and mechanism to impart a reciprocatory movement to said driver and plunger, whereby the prongs of said fastener may be clinched in a piece of material interposed between said support and anvil.

3. A mechanism for setting an annular pronged fastener having, in combination, a driver provided with an annular groove adapted to receive the head portion of said fastener, a spring-actuated plunger in said driver adapted to frictionally engage the inner face of said annular fastener and hold it positioned thereon, the forward end of said plunger normally projecting out of said driver beyond the annular groove therein, an anvil in alignment with said driver, a support for said fastener comprising a stationary member and a pair of fingers pivoted thereto normally interposed between said driver and anvil and movable toward and away from each other, and a spring acting to move them toward each other, and means to impart a reciprocatory movement to said driver and plunger, whereby a fastener positioned in said fingers will be engaged and gripped by said driver and plunger, the fastener pushed through between said fingers and its prongs clinched in a piece of material interposed between the fingers and anvil.

In testimony whereof I have hereunto set my hand.

ARTHUR R. HAVENER.
